(57) **CLAIM**

The ornamental design for a customer premises equipment device, as shown and described.

DESCRIPTION

FIG. 1 is a front perspective view of the customer premises equipment device.

FIG. 2 is a front elevation view of the customer premises equipment device.

FIG. 3 is a right side elevation view of the customer premises equipment device. The left side elevation view of the customer premises equipment device is a mirror image of the right side elevation view of the customer premises equipment device.

FIG. 4 is a top view of the customer premises equipment device; and,

FIG. 5 is a rear elevation view of the customer premises equipment device.

The broken lines shown in the figures that are immediately adjacent to the areas included in the claim and define unshaded regions represent the bounds of the claim. All other broken lines, including the features within broken line boundaries, are directed to environment. The broken lines form no part of the claimed design.
